UNITED STATES PATENT OFFICE.

WILLIAM H. NICKERSON, OF BROOKLINE, MASSACHUSETTS.

SHOE-SHANK STIFFENER.

Application filed November 4, 1927. Serial No. 231,015.

This invention relates to a shank stiffener incorporated between the shank portions of the outer and inner soles of a shoe, and extending from the heel portion to approximately the ball portion, to maintain the arched formation of the shank portion of the shoe.

The object of the invention is to provide a shank stiffener provided at its forward end 10 portion with a metatarsal arch supporter which is located at a predetermined height in a completed shoe, by the seating or bearing of the forward end portion of the stiffener on the outsole, and is formed to cooperate with an 15 inner sole portion above it, in providing an upwardly projecting protuberance on the shoe bottom, adapted to properly support the metatarsal arch of the wearer.

Of the accompanying drawings forming a 20 part of this specification,—

Figures 1, 2, 3, 4, 5, and 6 are top views of different forms of shank stiffener in which the invention is embodied.

Figure 7 is a section on line 7—7 of Figure 25 1.

Figure 8 is a section on line 8—8 of Figure 1.

Figure 9 is a section on line 9—9 of Figure 5.

Figure 10 is a section on line 10—10 of Figure 5.

Figure 11 is a section on line 11—11 of Figure 4.

Figure 12 is a section on line 12—12 of Figure 35 4.

Figures 13 and 14 are fragmentary sectional views, showing modifications.

The same reference characters indicate the same parts in all of the figures.

40 20 designates a shank stiffener, which may be of any suitable material, preferably sheet steel, although other materials may be employed. The stiffener is longitudinally arched between its rear or heel and forward ends,

45 to maintain any desired arched formation of the shank portion of a shoe bottom, the length of the stiffener being such that it is adapted to extend from the heel portion to approximately the ball portion of the bottom.

50 The cross section of the stiffener, shown by Figures 1 and 2, is flat, as indicated by Figures 7 and 8. The stiffener shown by Figures 3, 4 and 6, is molded transversely, so that it has a salient longitudinal ridge on its under side, 55 conforming to the ridge on the under side of an outer sole shank of the "cottage roof" type,

the cross section of the ridged portion of the shank being as shown by Figure 12.

In each of the forms above described, the under side of the stiffener is adapted to bear 60 from end to end and from edge to edge on the shank portion of an outer sole.

The stiffener shown by Figure 5, has a salient longitudinal ridge on its upper side, its under side being reentrant, as shown by Figures 65 9 and 10. The ridge is interrupted by a longitudinal slot 22, which imparts both longitudinal and transverse flexibility to the ridged portion, the edges of the slot being adapted to be flexed inward and downward. 70

In each of the illustrated forms, the under side of the stiffener is adapted to bear from end to end on the upper side of the shank portion of an outersole, although not necessarily from edge to edge, the form shown by Figures 5, 9 and 10 being such that only the longitudinal edges and the ends of the stiffener bear on the outer sole. 75

The stiffener is characterized in each embodiment of the invention by an upwardly 80 projecting convex metatarsal arch supporter 25, projecting wholly from the upper side of the forward end portion of the stiffener, so that the lower side of the forward end portion is entirely below the arch supporter, and 85 serves, by its bearing on an outer sole, to locate the arch supporter 25, at a predetermined height, so that in a completed shoe, the arch supporter and a portion of an inner sole bearing thereon constitute a protuberance projecting 90 into the foot-receiving space, and adapted to support the metatarsal arch of the wearer.

The arch supporter 25 extends substantially 95 from one longitudinal edge of the stiffener to the other, and has a dome-shaped upper surface, curving upwardly from the margin to the center of the supporter. Said margin may be oblong, or substantially elliptical, as shown by Figures 1, 3, 4, and 5, or circular, 100 as shown by Figures 2 and 6. When the margin is oblong, the major axis of the supporter may be at right angles with the longitudinal median line of the stiffener, as shown by Figures 1 and 5, or oblique to said 105 median line, as shown by Figures 3 and 4. I prefer to make the arch supporter and stiffener in separate parts and connect them by suitable means, for example, flexible tongues 27, bent over portions of the stiffener. 110 One of the tongues may be bent over the margin of a hole 28 in the stiffener, and the others

over the margin of the stiffener. The hole may be omitted in some cases, as shown by Figure 6. The connecting means may be a rivet 29, as shown by Figure 14. The arch 5 supporter may be hollow, as shown by Figure 13, or solid, as shown by Figures 7, 10, 11 and 14. When attached by a rivet 29, the supporter may be made of compressible material, such as vulcanized rubber.

10 When the stiffener includes a longitudinal ridge and a flat portion 31, at the forward end of the ridged portion, which is the case in certain stiffeners, particularly those of the "cottage roof" type, the supporter 25 is 15 formed to bear both on the end portion 31, and on a part of the arched and ridged portion, as shown by Figures 6, 10 and 11.

I claim:

1. A shank stiffener adapted to be built 20 into a shoe between the inner and outer soles thereof, and comprising an elongated plate, arched longitudinally between its forward and rear ends, and a metatarsal arch sup-

porter secured to and projecting upward from said plate at the forward end thereof, said 25 supporter being of such form in vertical cross section as to provide a convex upper surface and having the entire area of its lower face within the margin of the plate.

2. A shank stiffener adapted to be built into 30 a shoe between the inner and outer soles thereof, and comprising an elongated plate, arched longitudinally between its forward and rear ends, and a metatarsal arch supporter secured to and projecting upward from said plate 35 at the forward end thereof, said supporter being of such form in vertical cross section as to provide a convex upper surface and having the entire area of its lower face within the margin of the plate, said plate and supporter being connected by interengaged marginal portions.

In testimony whereof I have affixed my signature.

WILLIAM H. NICKERSON.
